UNITED STATES PATENT OFFICE.

JOSEPH G. BIXBY, OF DECATUR, ILLINOIS, ASSIGNOR TO THE BIXBY COMPANY, OF DECATUR, ILLINOIS, A CORPORATION OF ILLINOIS.

BURIAL-SHOE.

1,179,067.

Specification of Letters Patent. Patented Apr. 11, 1916.

Application filed September 8, 1913. Serial No. 788,508.

To all whom it may concern:

Be it known that I, JOSEPH G. BIXBY, a citizen of the United States, a resident of Decatur, in the county of Macon and State 5 of Illinois, have invented new and useful Improvements in Burial-Shoes, of which the following is a specification.

My invention relates to improvements in burial shoes, and has for its objects the provision of a shoe of that character which readily conforms to the foot and particularly the ball of the foot and has a heel construction which permits the shoe to accommodate itself to variations in size.

15 A further object is the provision of a burial shoe which may be applied to the foot with ready facility and be a good fit.

A further object is the provision of a removable stiffening for the vamp portion 20 of the shoe so that the shoe is stiffened to hold its shape until used, when the removable stiffening is taken out so that the shoe fits the foot.

25 A further object is the improvement of various details whereby a light, cheap shoe, practical for its purpose is provided.

To the accomplishment of the foregoing and such other objects as may hereinafter appear, my invention consists in the construction, combination and arrangement of parts hereinafter specified and then sought 30 to be defined in the appended claims, reference being had to the accompanying drawing which illustrates a preferred embodiment of my invention, it being understood 35 however, that changes may be made in practice without digressing from my inventive idea.

In the drawing, Figure 1 is a perspective 40 view of a shoe constructed according to my invention, part of the covering or finishing material being removed. Fig. 2 is a perspective view showing the shoe in condition to be applied to a foot, the ends of the sole 45 being bent out of position for illustrative purposes. Fig. 3 is an elevation of the heel portion of the shoe. Fig. 4 is a detail section. Fig. 5 is a detail vertical section of the heel and counter construction without 50 showing the fabric.

In shoes of this character it is very desirable to have them constructed so that they will conform to the shape of the foot, and particularly the ball portion thereof. This 55 desirable feature is obtained by providing

a removable stiffening portion for the vamp, which may be taken out when the shoe is to be used, allowing it to fit the foot closely, the covering and finishing material being light and flexible. The heel is constructed 60 so that it may give or yield to permit the shoe to accommodate itself to any slight differences in size and permits of easy adjustment.

Referring now to the drawings, 1 designates the shoe as a whole, having the toe portion 2 and the heel portion 3, and the sole portion 4. The body, base or foundation of the shoe is formed of the stiffening fabric or material 5, which as shown in 70 Fig. 1 is so formed as to provide the toe-cap 6 and the counters 7, leaving a cut-out portion from the toe-cap to the counters. In the making of the shoe, this cut-out portion receives the removable stiffening portion 8, which stiffens the vamp and the ball of the shoe, and the edges of which conform to the edges of the stiffening fabric or material 5. This stiffening member 8 is detachably secured to the base fabric 5 by 80 means of the tapes or similar fastenings 9, the free ends 10 of the tapes projecting through the lining 11 of the shoe, as shown, the lining being loose in the shoe.

The sole 4 is composed of a suitable stiffening material or fabric, molded to conform 85 to the shape of the shoe, and having its edge turned over to form a bead, as shown at 12, Fig. 4, the underside of the heel portion 13 of the sole being pressed to provide a beaded or counter-sunk construction to receive the heel 14, as at 13', Fig. 5 which is secured thereto by cementing, pasting or tacking. A suitable covering material 15 is provided over the body portion and a covering material is also provided over the sole portion, being suitably secured thereto, by means of paste or cement, it being understood that the sole portion is secured to the body portion also by means of paste, cement 95 or similar adhesive. It is to be noticed as shown in detail in Fig. 4, that the covering material or fabric 15 extends only a short distance over the sole, the bead 12 serving as an additional holding means, strengthening the connection and necessitating the use of a comparatively small amount of covering material, which is usually expensive, as it must extend only a short distance over the sole.

Another advantageous feature of my invention is the heel construction. The end portions of the counters are hinged, as at 16, and their free ends normally held together by the elastic members 17. This construction readily permits the shoe to adapt itself to feet of different lengths or sizes and permits of easy adjustment on the foot.

A further detail of construction is the provision of the cut-out portions or notches 18 in the sides of the base or foundation material or fabric 5. This provides a flexibility for the shoe across the ball portion of the shoe rendering it easy to fit the foot.

The shoe is sold in substantially the shape shown in Fig. 1, and when it is desired to use the same the free ends 10 of the tapes 9 are drawn, thus releasing the removable stiffening member 8 from the base or foundation material or fabric 5, so that it may be withdrawn from under the lining. As stated before, this permits the shoe to accommodate itself to the shape of the foot, the extensible heel construction also assisting in providing a ready fit. The details of construction insure cheapness in manufacture and eliminate any unnecessary waste of material, at the same time providing a shoe that is sufficiently strong for the purpose.

What I claim is,—

1. A burial shoe including a base or foundation, and a covering and finishing material thereover, a portion of said base or foundation being removable so as to permit the shoe to readily conform to the shape of the foot.

2. A burial shoe including a base or foundation formed of stiffening material and having a vamp portion, and a covering and finishing material thereover, said vamp portion being removable so as to permit the shoe to conform to the shape of the ball of the foot.

3. A burial shoe including a base or foundation formed of stiffening material and having a vamp portion, a covering and finishing material thereover, and flexible means securing said vamp portion to the remainder of said base or foundation, said flexible securing means being detachable to permit said vamp to be removed.

4. A burial shoe including a body portion, the rear part of said body portion being split at the heel to provide separable counter portions, the end portions thereof being separately and independently hinged to said body portion and resilient means normally tending to draw said separable counter portions together whereby a yielding heel construction is provided to adapt the shoe to slight variations in size.

5. A burial shoe including a body portion and a sole portion, the sole being provided with a bead along its edge, and finishing and covering material for the body having

its lower edge fitting between the sole and body and secured therebetween, the bead forming an additional holding means for the finishing and covering material.

6. In a burial shoe, a base or foundation providing a toe cap and counters and having a space therebetween, a removable member fitting said space to provide a vamp stiffening means, and means for detachably securing said vamp stiffening means to said base or foundation.

7. In a burial shoe, a base or foundation providing a toe cap and counters and having a space therebetween, said base or foundation being notched adjacent the ball portion, a removable member fitting said space to provide a vamp stiffening means, and means for detachably securing said vamp stiffening means to said base or foundation.

8. In a burial shoe, a base or foundation, a sole member having an upwardly turned bead along its edge to fit the bottom of said base or foundation, the heel portion of said sole also having a downwardly turned bead to provide a countersunk construction, a heel fitting said countersunk construction and a covering and finishing material over said base or foundation and extending between said base or foundation and said sole member.

9. A burial shoe including a body portion, said body portion being split at the heel to provide separable counter portions, the end portions thereof being separately and independently hinged to said body portion, and resilient means secured to the inside of said hinged end portions normally tending to draw them together, whereby a yielding heel construction is provided.

10. A burial shoe including a base or foundation formed of stiffening material and having a vamp portion, a covering and finishing material thereover, and flexible means securing said vamp portion to the remainder of said base or foundation, said flexible securing means being detachable to permit said vamp to be removed and consisting of a member on each side of said shoe with a free portion folded back from adjacent the toe so that its end is near the heel.

11. A burial shoe including a base or foundation formed of stiffening material and having a vamp portion, a covering and finishing material thereover, and flexible means securing said vamp portion to the remainder of said base or foundation, said flexible securing means being detachable to permit said vamp to be removed and consisting of a member on each side of said shoe with a free portion folded back from adjacent the toe so that its end is near the heel, and a lining through which the ends of said flexible securing means project.

12. A burial shoe including a base or foundation having a vamp portion, a cover-

ing and finishing material thereover, and means for detachably connecting the vamp portion of said base or foundation to the remainder of said base or foundation, said 5 vamp portion being adapted to be removed to permit the shoe to conform to the shape of the foot.

In testimony whereof, I affix my signature in the presence of two subscribing witnesses.

JOSEPH G. BIXBY.
